UNITED STATES PATENT OFFICE

JOSEPH A. MEYERS AND HENRY HEAD JOHNSON, OF LOS ANGELES, CALIFORNIA, AS-SIGNORS TO J. A. MEYERS AND COMPANY, INC., OF LOS ANGELES, CALIFORNIA, A CORPORATION OF CALIFORNIA

DESIGN FOR A RING

Application filed March 1, 1930. Serial No. 34,711. Term of patent 14 years.

To all whom it may concern:

Be it known that we, JOSEPH A. MEYERS and HENRY HEAD JOHNSON, citizens of the United States, residing at Los Angeles, in the county of Los Angeles and State of California, have invented a new, original, and ornamental Design for a Ring, of which the following is a specification, reference being had to the accompanying drawings, forming a part thereof.

Figure 1 is a plan view of a ring showing my new design.

Fig. 2 is a side elevation thereof.

Fig. 3 is a side elevation thereof looking from the reverse of Fig. 2.

The design is primarily directed to the ring mounting and it is contemplated later to employ different stones in the ring so far as may be done without changing applicant's invention.

We claim:

The ornamental design for a ring as shown and described.

Signed at Los Angeles, in the county of Los Angeles, and State of California, this 14th day of February, 1930.

JOSEPH A. MEYERS.
HENRY HEAD JOHNSON.
